UNITED STATES PATENT OFFICE.

DAVID D. NOLLEY, OF WILSON, NORTH CAROLINA.

DESIGN FOR A LATCH.

SPECIFICATION forming part of Design No. 20,480, dated January 13, 1891.

Application filed November 15, 1890. Serial No. 371,604. Term of patent 7 years.

To all whom it may concern:

Be it known that I, DAVID D. NOLLEY, of Wilson, in the county of Wilson and State of North Carolina, have invented certain new and useful Improvements in Designs for Latches; and I do hereby declare the following to be a full, clear, and exact description of the invention, such as will enable others skilled in the art to which it pertains to make and use it, reference being had to the accompanying drawings, which form part of this specification.

My invention relates to an improvement in designs for latches; and it consists in a latch having at its free end the figure of an animal, which imparts to the latch a more attractive appearance.

The accompanying drawing represents a design which embodies my invention.

A represents a hasp or latch, which is pro-

vided with an opening D, and in this opening is formed the vertical projection G. The outer or free end of the latch is given the outline of a hog or other similar animal.

By giving the latch the configuration or shape of an animal it is rendered much more pleasing and attractive to the eye than if it were made perfectly plain in the usual manner.

Having thus described my invention, I claim—

A design for a latch, substantially as herein shown and described.

In testimony whereof I affix my signature in presence of two witnesses.

DAVID D. NOLLEY.
